UNITED STATES PATENT OFFICE.

MARTIN D. WAHL, OF ALLSTON, MASSACHUSETTS.

FOLDING GARMENT-HANGER.

1,058,394.

Specification of Letters Patent.

Patented Apr. 8, 1913.

Application filed August 28, 1912. Serial No. 717,526.

To all whom it may concern:

Be it known that I, MARTIN D. WAHL, a citizen of the United States, and resident of Allston, county of Suffolk, State of Massachusetts, have invented an Improvement in Folding Garment-Hangers, of which the following description, in connection with the accompanying drawings, is a specification, like letters on the drawings representing like parts.

My invention is a garment hanger especially constructed for folding into a practically solid package adapted to be carried in the coat pocket, or in a pocket in a traveling bag, and to this end it consists of a plurality of jointed parts so curved and connected together as to fold flat against each other, both in a vertical plane and a horizontal plane to constitute a substantially rectangular body when folded, and, when opened, to be exceedingly strong to resist the strains naturally brought thereon in use. The hanger is preferably of wood and provided at its middle with a suspending hook, which cooperates with the middle joint or vertical pivot to removably lock the members in extended position, while permitting them quickly to be unlocked and swung around on said vertical pivot horizontally flat against each other. Each side piece or portion at the opposite sides of this central vertical pivot is curved in a reverse curve and made in two parts joined by a horizontal pivoting union, preferably in the form of a double hinge, permitting the outer part, therefore, to turn upwardly and over on to the inner portion, so that the convex top edge of said outer portion will turn down against the concave top edge of the inner portion, and yet when the parts are extended the hinge is in the position of greatest strength to maintain the garment hanger stable and resist the carrying strains of the coat or garment which is supported thereon.

In the drawings, Figure 1 shows the garment hanger in front elevation, parts being broken away to show the detailed construction of the double hinge connection; Fig. 2 is an enlarged front elevation of the garment hanger folded; and Fig. 3 is a view of the latter in top plan.

The garment hanger proper consists of opposite end portions 1, 2 and adjacent intermediate portions 3, 4, the latter being tapering so as to have the greatest vertical height at their meeting ends at the middle

of the garment hanger. At said meeting ends I provide a hinge 5 having a vertical pivot so as to permit the opposite halves of the garment hanger to swing horizontally together. The hinge 5 is preferably secured on the back side of the garment hanger, and pivoted on the opposite or front side thereof on a horizontal pivot 6 is a locking plate 7 for holding the parts together, herein shown as notched at 8 to lock under the head of a screw or headed pin 9. Projecting rigidly from the center of said holding plate or locking plate 7 is a suspending loop 10, herein shown as open at one side to constitute a hook 11. The meeting ends of the parts 1, 3 and 2, 4 are provided with a central vertical kerf 12, 13, and snugly fitted in the upper portion of said kerf is a hinge plate or connection 14 pivotally secured in the kerf by horizontal pivots 15, 16. The plate 14 preferably has oblique ends fitting snugly against the corresponding oblique ends of the kerf 12, 13 when in the position of Fig. 1, and when in this position the adjacent ends of the parts 1, 3 and 2, 4 abut beneath said hinge, so as to give additional strength. The parts 1, 2 preferably curve downwardly at their outer ends, while the parts 3, 4, curve in an opposite direction, as clearly shown in Fig. 1 so as better to conform to the shape required for supporting a coat, and at the same time permit the parts to nest compactly together when folded, as shown in Figs. 2 and 3.

I am aware that folding garment hangers of various kinds have heretofore been suggested, made up of four parts folding over and over, and others composed of two parts folding together, and accordingly it will be understood that my invention is limited to the precise improvements above described. When the parts are folded the supporting member 10 and locking member 7 are turned on the pivot 6 to the position shown in Fig. 100 2, the hook 11 being preferably of about the same width as the folded wooden portions, and the holder plate 7 laps flat against the free end of the outer member 2, as clearly shown in Figs. 2 and 3. By combining the 105 horizontally pivoted outer arrangement with the vertically pivoted middle arrangement, great strength is secured, notwithstanding the light construction, and by combining the variously curved parts with these horizontally pivoted and vertically pivoted constructions, an exceedingly compact hanger is 110

provided when folded, while the supporting and locking arrangement unites with the aforesaid parts and constructions to give strength, compactness and neatness to the combination.

In use a number of these garment hangers can be carried in a traveling bag or suit case or trunk without wasting any space, and, while occupying a very small space, 10 because of their rectangular shape when folded, as shown in Figs. 2 and 3. When it is desired to use one of the hangers its hook or suspending wire 10 is turned up slightly or suspending wire 10 is turned up slightly 15 farther than shown in Fig. 1, and the two halves of the body of the hanger are swung away from each other on the pivot 5 until the headed pin 9 comes above the notch 8, whereupon the plate 7 is lifted into engagement with the pin 9 beneath said head, so as 20 to lock the middle parts 3, 4 in rigidly extended position. The ends 1, 2 are then raised and turned down on their horizontal pivots to the positions shown in Fig. 1, the relatively long hinge plates 14 with their 25 oblique ends holding the end portions 1, 2 rigidly against improper downward movement and against any sidewise movement whatever in a horizontal plane.

Having described my invention, what I 30 claim as new and desire to secure by Letters Patent is:

1. A folding garment hanger, comprising a multi-part body having central portions joined by a vertical pivot and horizontally 35 pivoted end portions, and a supporting member movable from supporting position into horizontal alinement with the body parts when folded together, said supporting member and the adjacent part of the body 40 having coöoperating parts constituting a lock movable into locking position when the supporting member is moved into supporting position.

2. A folding garment hanger, comprising 45 two central parts united by a vertically pivoting hinge secured thereto at one side of the garment hanger, and end portions, the inner ends of said end portions and the outer ends of said central parts having vertical kerfs with oblique inner ends approaching each other at the top of the 50 hanger, and hinge plates with correspondingly oblique ends pivoted on horizontal

pivots in each kerf to abut against said oblique ends of the kerfs when the garment 55 hanger is extended, and a supporting and locking device horizontally pivoted on one of said central parts on the side of the hanger opposite said vertically pivoting hinge, a pin-like part secured to the adjacent end of the adjacent central part on the same side thereof as said device, and the latter having a locking portion extending horizontally to engage said pin-like part when the supporting and locking device is turned on its said horizontal pivot into position for supporting the hanger.

3. A folding garment hanger, comprising two central parts united by a vertically pivoting hinge secured thereto at one side of 70 the garment hanger, and end portions, the inner ends of said end portions and the outer ends of said central parts having vertical kerfs with oblique inner ends approaching each other at the top of the 75 hanger, and hinge plates with correspondingly oblique ends pivoted on horizontal pivots in each kerf to abut against said oblique ends of the kerfs when the garment hanger is extended, and a supporting and locking device horizontally pivoted on one 80 of said central parts on the side of the hanger opposite said vertically pivoting hinge, a pin-like part secured to the adjacent end of the adjacent central part on 85 the same side thereof as said device, and the latter having a locking portion extending horizontally to engage said pin-like part when the supporting and locking device is turned on its said horizontal pivot into position for supporting the hanger, the top edges of said central parts being concave and sloping downwardly toward the extremities of the hanger 90 and the outer portions having their top 95 edges convex to nest compactly against the said concave edges when the garment hanger is folded.

In testimony whereof, I have signed my name to this specification, in the presence of 100 two subscribing witnesses.

MARTIN D. WAHL.
